FLOW CONTROL VALVE

Aladar O. Simko, Detroit, Mich., assignor to Ford Motor Company, Dearborn, Mich., a corporation of Delaware

Filed Apr. 20, 1964, Ser. No. 361,199

6 Claims. (Cl. 137—540)

This invention relates to a fuel injection system. More particularly, it relates to the construction of a delivery valve for controlling the flow between a pump and an injection nozzle not only to limit the backflow of fuel into the system after each pump stroke, but also to reduce the residual pressure in the nozzle delivery line.

The known fuel injection pumps of the type to which the invention is directed generally have a number of reciprocating plungers each intermittently delivering a charge of fuel past a delivery valve to an injection nozzle. The delivery valve is provided for a number of reasons. One is to limit the amount of fuel backflow into the pump pressure chamber so that if an air pocket is trapped in the high pressure line, it can be driven out on successive pressure strokes of the pump plungers. Otherwise, the air pocket would expand during the decrease in pump pressure, and would not be driven out of the delivery line. In any practical case, one delivery cycle does not displace enough fuel past the injection nozzle to compress the air pocket to the opening pressure of the nozzle.

A second reason for the provision of the delivery valve is to reduce the residual pressure in the high pressure delivery line after each stroke of the pump plunger. This prevents secondary injection due to reverberation of pressure waves in the closed high pressure line when superimposed on high residual pressure.

The above functions generally are accomplished by constructing the delivery valve to retract a finite or predetermined small volume of its mass out of the high pressure delivery line during the non-pressure stroke of the pump plunger. That is, expand the high pressure line by a finite amount. There is a basic difficulty, however, with such a construction. Separate delivery valves are required for each injection nozzle and pump plunger, and since a typical system may have six or more delivery valves, each of the valves must be manufactured to extremely close tolerances so that each of the valves will always retract the same precise volume. Without such control, the delivery through each of the nozzles might be quite different even though the pump plungers deliver the same quantity of fuel. An unbalanced situation would result wherein each of the nozzles delivered a different quantity of fuel, thereby requiring considerable adjustment and maintenance for the engine to run efficiently. This poses both manufacturing and wear problems, therefore.

The invention eliminates these disadvantages by separating the two functions of the delivery valve. The delivery valve of the invention includes a pressure sensitive diaphragm valve that seats immediately after the pump stroke to cut off return flow of fuel into the pump pressure chamber. Subsequently, the residual pressure in the injector delivery line is reduced by expanding the volume of the line. That is, the high pressure in the delivery line balloons the diaphragm until one of two conditions occurs; either the pressure forces on opposite sides of the diaphragm become balanced; or, the internal expansion reaches a predetermined maximum. As to this last condition, a control is provided that permits an internal expansion beyond that needed for air-free operation, but less than the volume of fuel to be injected during each pumping stroke of the plungers.

It is an object of the invention, therefore, to provide a unidirectional flow valve assembly for controlling the flow of fluid between two varying pressure lines that not

only controls the return flow of fuel, but reduces the residual pressure in one line until the pressure forces on opposite sides of the valve are in equilibrium or balanced.

It is a further object of the invention to provide a delivery valve for controlling the flow of fuel between a fuel injection pump and nozzle, the valve including a pressure sensitive diaphragm valve element that seats upon a drop in the inlet line pressure to block return fuel flow; the diaphragm subsequently moving in response to the residual pressure in the delivery line to increase the internal volume of the delivery line until one of two conditions is met; either the pressure forces acting on opposite sides of the diaphragm become balanced; or, the increase in internal volume reaches a predetermined maximum.

It is a further object of the invention to construct a fuel injection system delivery valve with a pressure sensitive diaphragm that permits a continuous expansion of the internal volume of the delivery line subsequent to the seating of the valve to block return flow from the line to the pump internal system.

A still further object of the invention is to provide a fuel injection system delivery valve that is simple in construction, economical to manufacture, and operates in an efficient manner.

Other objects, features, and advantages of the invention will become apparent upon reference to the succeeding, detailed description thereof, and to the drawings illustrating a preferred embodiment thereof; wherein,

FIGURE 1 shows a portion of a fuel injection system incorporating a known type of delivery valve; and,

FIGURES 2, 3, 4 and 5 are cross-sectional views of a delivery valve constructed according to the invention and illustrated during successive phases of operation in the successive figures.

FIGURE 1, which is essentially to scale, shows a portion of a known fuel injection apparatus. It has a housing 10, the lower portion of which rotatably supports a shaft 12 that is driven, for example, by the camshaft of an internal combustion engine. A wobble plate 14, having a cam surface 15, is fixed to the end of shaft 12, as is the lower end of a rotary valve 16. The valve rotates within a bore 18 in housing 10, and is formed with suitable spaced lands 20 and 22. The lands are connected by a reduced neck portion 24 providing an annular fuel chamber 26. The valve controls the flow of fuel between an inlet line 28 and a bore 30 in a known manner; that is, it has a flow cutoff portion 32 for progressively blocking or opening the connections and controlling spillage of fuel from bore 30 back into chamber 26.

Wobble plate 14 slidably supports a number (only one shown) of non-rotating spaced slipper elements 34, the number varying with the design of the pump. Each of the slippers has a cup-shaped recess 36 receiving the spherical end 38 of a tappet 40 enclosing one end of a pump plunger 42. The tappet has a sliding sealed fit within a bore 43 in housing 10, its upper radial movement being terminated by abutment against a stop plate 46. The stop plate is seated on a stepped portion 48 in housing 10, and is apertured for slidably receiving the stem or neck portion 50 of plunger 42. The plunger has a spherical portion 52 at its tappet end, and a cylindrical piston-like portion 54 at the opposite end. The piston portion slides in the lower portion of a bore 56 having an upper compression chamber portion 58 opening directly into a chamber 60 in the cover portion of housing 10. The flow between the two chambers is controlled by a spring seated non-return flow delivery valve 62 of a known construction. The chamber 58 is intersected by the cross bore 30 that is closed at one end by plug 64.

Plunger 42 is based to its bottom dead center position by a spring 66 that surrounds stem 50 and is seated between plate 46 and the plunger end 52.

In operation, rotation of drive shaft 12 rotates cam plate 14 to force plunger 42 upwardly through its compression or pumping stroke, while permitting it to descend through its suction stroke under the force of spring 66. During the suction stroke, fuel is drawn into bore portion 58 from bore 30, rotary valve 16 at this time connecting line 28 and bore 30. During the first part of the up-stroke of plunger 42, the rotary valve cutoff portion 32 maintains bore 30 open, and fuel spills from bore portion 58 back through bore 30. Actual delivery of fuel past delivery valve 62 takes place during the mid-portion of the plunger stroke when the rotary valve cutoff 32 has moved to a position closing bore 30. When this occurs, continued upward movement of plunger 42 compresses the fuel in bore 58 and causes valve 62 to be lifted off its seat, so that a high pressure charge of fuel is injected into line 72 and out through injector 74. During the final portion of the plunger pumping stroke, the rotary valve cutoff portion 32 will uncover bore 30 and permit spillage of fuel back into the valve chamber 26. This will continue until the plunger piston portion 54 reaches its top dead center position. Thus, it will be seen that the rotary motion of drive shaft 12 will reciprocate each of the plunger pistons in timed relationship, and, therefore, intermittently inject charges of fuel into chamber 60.

The delivery valve 62, as stated previously, is a check or non-return flow type valve; that is, it moves out of bore portion 58 in response to the fuel pressure in the bore during the ascending compression stroke of the plunger, the fuel being discharged past the valve into delivery line 72. The injector nozzle 74 is of a known construction, and its details, therefore, are not given. It remains closed below a predetermined injection pressure. The charge of fuel that is discharged into line 72, therefore, rises in pressure up to the injector opening pressure, at which point a predetermined volume of fuel is injected from the nozzle into the engine combustion chamber, not shown.

The discharge valve 62 shown in FIGURE 1 represents a known poppet-type valve. It has a generally conical upper land 76 joined to a spaced cylindrical land 78 by a reduced diameter neck portion 80. The conical land 76 is adapted to seat against a mating tapered surface 88 formed in the upper portion of pump housing 10. The valve has a lower guide portion 86 that is fluted or slotted so that fuel in bore portion 58 can act on the underside of land 78. The valve is biased to its seated flow blocking position by a spring 90.

During the last part of the compression stroke of plunger 42, rotary valve 16 attains a position permitting spillage of fuel from bore portion 58 back into bore 30. The pressure in bore 58 then drops and the spring 90 and higher pressure in line 72 causes the land 78 of valve 62 to begin to enter the cylindrical portion of bore 58. As soon as the lower edge of land 78 contacts the bore wall, fuel flow between bore portion 58 and chamber 60 becomes blocked. At this moment, the pressure in line 72 is substantially equal to the nozzle injection closing pressure. However, the valve continues its downward movement until the conical land 76 seats on the surface 88; this continued movement retracts a definite area or volume of the valve into the bore 58 and out of the chamber 60. The volume of chamber 60, therefore, is increased, and the residual pressure in line 72 and chamber 60 is thereby reduced by the finite amount defined by the movement of land 78 into bore 58.

As discussed previously, a delivery valve such as valve 62, operates on the principle of retracting a finite volume during the suction stroke of the pump plunger. This is disadvantageous because of the close tolerance requirements necessary during manufacture of the valve so that all of the valves of the pump assembly will retract exactly the same volume.

A simpler delivery valve constructed according to the invention is shown in FIGURES 2 through 5. FIGURE 2

shows the pump housing 10 having a recessed portion providing a T-shaped chamber 100. The chamber is connected at one end to the fuel delivery line 72, and faces a smaller diameter T-shaped chamber 102 connected to bore portion 58. The delivery valve comprises a flexible annular rubber or other suitably constructed diaphragm 104 positioned between thin flat discs 106 and 108. Disc 106 has a smaller diameter than the recess 110 so as to be radially movable within it, in a manner to be described. A spring 112 biases the disc 110 against diaphragm 104. A larger force spring 114 biases disc 106 against the diaphragm to sealingly seat the diaphragm edges against the valve body and thereby block flow between bore portion 58 and line 72. Disc 106 has a restricted opening 118 permitting the fuel in delivery line 72 to act on the upper portion 122 of the diaphragm. The underside 124 of the diaphragm is acted upon by the fuel in bore portion 58.

It will be clear from the above that fuel delivery will begin when the valve 16 has rotated to block spillage back through bore 30 and cause the fuel pressure to build up in bore portion 58. When the combined forces of spring 112 and the fluid pressure in bore portion 58, acting on the disc 108 and underside 124 of the diaphragm, are greater than the forces due to spring 114 and the pressure in line 72 acting through hole 118 on the diaphragm, the fuel in bore portion 58 will move diaphragm 104 and disc 108 upwardly away from the flat valve body seat 126 to permit flow into chamber 100 around the edges of the valve. The pressure in line 72 will then be sufficient to open the nozzle 74, and a charge of fuel will be ejected. This condition of operation is shown in FIGURE 3.

When control valve 16 rotates to a position unblocking bore 30 during the last portion of the compression stroke of the pump plunger, thereby permitting spillage of fuel from bore portion 58, the pressure in bore portion 58 will decrease to a level lower than the combined forces of spring 114 and the residual pressure in line 72. The injector will close, and diaphragm 104 and discs 106 and 108 will then return to the positions shown in FIGURE 2, cutting off flow between line 72 and bore portion 58. At this point, the residual pressure in line 72 is substantially equal to the injection nozzle closing pressure. Upon continued decrease in the pump pressure in bore portion 58, the higher residual fluid pressure force acting through hole 118 on the upper part of the diaphragm will force the central portion of the diaphragm to balloon downwardly into the recess 110, as illustrated in FIGURE 4. This provides an expansion or increase in the internal volume of chamber 100, and, therefore, decreases the residual pressure in line 72. This downward movement of the diaphragm will continue until the combined forces acting against the opposite sides of the diaphragm are balanced. Thus, it will be seen that the delivery valve is capable of providing a variable increase in the internal volume of chamber 100, and one that is proportionate to the decrease in pressure on the inlet side of the valve.

The recess 110 is provided with a beveled or tapered edge 128 and a step 130 that act as stops for the downward movement of the diaphragm. They assure that the delivery valve will not increase the volume in chamber 100 by an amount greater than the maximum displacement of fuel during any one upstroke of the pump plunger. That is, the diaphragm can move downwardly as long as the disc 110 and the edges of the diaphragm are free to move. Once they rest against the edge 128 and shoulder 130, further expansion of the internal volume of chamber 100 and line 72 is prevented. This particular condition is illustrated in FIGURE 5. This assures that some fuel will be forced into line 72 during every delivery cycle, so that the pressure of any air pocket that initially may be present in line 72 will gradually rise to the opening pressure of nozzle 74, and be driven out.

Thus, it will be seen that the delivery valve performs two functions. First the diaphragm valve seats on sur-

face 126 to block return flow of fuel from line 72 to the pressure chamber 58. Secondly, the central portion of diaphragm 106 is forced downwardly, progressively increasing the internal volume of chamber 100 and decreasing the residual pressure in line 72. This will continue until the pressure forces on opposite sides of the diaphragm are balanced, as shown in FIGURE 4, or until the movement has continued up to the permissible predetermined maximum increase in the internal volume of chamber 100, at which point the diaphragm will be in the position shown in FIGURE 5.

The pumping phase of operation is accomplished in the reverse manner; that is, the higher combined forces acting on the underside of the diaphragm move it progressively through the phases from the positions indicated in either FIGURES 5 or 4 to FIGURE 2, and then to the position illustrated in FIGURE 3, at which point flow is permitted between the bore 58 and delivery line 72.

From the foregoing, it will be seen that the invention provides a flow control valve that permits flow in one direction while preventing return flow, and subsequently reduces the residual pressure on the delivery side of the valve by an expansion or increase in the internal volume of the delivery line. The invention also provides a construction that forces air pockets out of the system and assures a delivery of fuel during each delivery cycle.

The invention further assures equal delivery through each nozzle by maintaining a near equal volume for every high pressure line-nozzle assembly, and equal force springs acting on the inlet sides of the diaphragms. Since the fuel has a very high modulus of elasticity, slight variations in the delivery line volume and the residual pressure of the fluid therein between different assemblies will result only in negligible variations in volume delivered through the nozzle with equal delivery from the plungers.

While the invention has been illustrated in connection with a fuel injection system, it will be clear to those skilled in the arts to which the invention pertains that it would have use in other installations, and that many changes and modifications may be made thereto without departing from the scope of the invention.

1. Fluid flow control means comprising, a fluid inlet line containing a fluid that varies in pressure, a fluid discharge line having means therein blocking its outlet below a predetermined pressure of fluid therein, and unidirectional flow control valve means between said inlet line and the inlet to said discharge line and movable in response to differential fluid pressure forces between said lines acting in one and the opposite directions to communicate or block, respectively, flow between said lines, said valve means having control means movable in response to a differential fluid pressure force acting in the opposite direction to block said flow and balance the pressures in said lines, said valve means comprising a valve bore connecting said lines and having a valve seat therein, a diaphragm in said bore adapted to engage said seat to block flow between said lines, a valve member adapted to overlay said diaphragm, means biasing said valve member and diaphragm against said seat to block the said flow, said valve member having an aperture therein admitting fluid from said discharge line to act on one side of said diaphragm, said diaphragm being acted upon on its opposite side by the fluid in said inlet line, said discharge line fluid ballooning a portion of said diaphragm to increase the volume and decrease the pressure in said discharge line until the fluid pressure forces on opposite sides of said diaphragm are balanced, and means operable above a predetermined differential in said fluid pressure forces to limit ballooning of said diaphragm.

2. Fluid flow control means comprising, a fluid inlet line containing a fluid that varies in pressure, a fluid discharge line having means therein blocking below a predetermined pressure of fluid therein, and unidirectional flow control valve means between said inlet line and the

inlet to said discharge line and movable in response to differential fluid pressure forces between said lines acting in one and the opposite directions to communicate or block, respectively, flow between said lines, said valve means having control means movable in response to a differential fluid pressure force acting in the opposite direction to block said flow and balance the pressures in said lines, said valve means comprising a valve bore connecting said lines and having a valve seat therein, a diaphragm in said bore adapted to engage said seat to block flow between said lines, a valve member adapted to overlay said diaphragm, means biasing said valve member and diaphragm against said seat to block the said flow, said valve member having an aperture therein admitting fluid from said discharge line to act on one side of said diaphragm, said diaphragm being acted upon on its opposite side by the fluid in said inlet line, said discharge line fluid ballooning a portion of said diaphragm to increase the volume and decrease the pressure in said discharge line until the fluid pressure forces on opposite sides of said diaphragm are balanced, or until the discharge line volume has increased a predetermined amount, and means operable above a predetermined differential in said fluid pressure forces to limit ballooning of said diaphragm.

3. Fluid flow control means comprising, a fluid inlet line containing a fluid that varies in pressure, a fluid discharge line having means therein blocking its outlet below a predetermined pressure of fluid therein, and unidirectional flow control valve means between said inlet line and the inlet to said discharge line and movable in response to differential fluid pressure forces between said lines acting in one and the opposite directions to communicate or block, respectively, flow between said lines, said valve means having control means movable in response to a differential fluid pressure force acting in the opposite direction to block said flow and balance the pressures in said lines, said valve means comprising a valve bore connecting said lines and having a valve seat therein, a diaphragm in said bore adapted to engage said seat to block flow between said lines, a valve member adapted to overlay said diaphragm, means biasing said valve member and diaphragm against said seat to block the said flow, said valve member having an aperture therein admitting fluid from said discharge line to act on one side of said diaphragm, said diaphragm being acted upon on its opposite side by the fluid in said inlet line, said discharge line fluid ballooning a portion of said diaphragm to increase the volume and decrease the pressure in said discharge line until the fluid pressure forces on opposite sides of said diaphragm are balanced, or until the discharge line volume has increased a predetermined amount, and means operable above a predetermined differential in said fluid pressure forces to limit ballooning of said diaphragm.

4. Fluid flow control means comprising, a fluid inlet line having a valve seat and containing a fluid that varies in pressure, a fluid outlet line connected to said inlet line and means therein normally a discharge portion below a predetermined pressure of the fluid therein, and unidirectional flow control valve means between said lines movable away from or against said valve seat by and in response to differential fluid pressure forces between said lines resulting from changes in the fluid pressure in said inlet line, said differential forces acting on said valve means in one and the opposite directions to communicate or block, respectively, flow between said lines, said valve means having flexible control means movable first against said valve seat in response to a differential fluid pressure force acting in the opposite direction resulting from a lowering of the pressure in said inlet line below the said predetermined fluid pressure level at which said outlet line is blocked to block said flow and subsequently being deformed towards said inlet line in response to a predetermined rise in said differential force, and means operable above a predetermined pressure of the fluid in said outlet line to limit the movement of said control means toward said inlet.

5. Fluid flow control means comprising, a fluid inlet line having a valve seat and containing a fluid that varies in pressure, a fluid outlet line connected to said inlet line and means therein normally a discharge portion below a predetermined pressure of the fluid therein to define a chamber of a predetermined volume in said line, and non-return flow valve means between said lines movable away from or against said valve seat by and in response to differential fluid pressure forces between said lines resulting from a lowering of the pressure in said inlet line below the said predetermined fluid pressure level at which said outlet line is blocked acting on said valve means in one and the opposite directions to communicate or block, respectively, flow between said lines, said valve means having flexible control means movable first against said valve seat in response to a differential fluid pressure force acting in the opposite direction resulting from a lowering of the pressure in said inlet line below the said predetermined fluid pressure level at which said outlet line is blocked to block said flow and subsequently being deformed towards said inlet line in response to a predetermined use in said differential force to increase the volume and reduce the residual pressure in said chamber, and means to limit the movement of said control means toward said inlet above a predetermined increase in volume of said chamber.

6. A delivery valve assembly comprising, a valve bore having a seat therein, fluid inlet and outlet lines connected to different portions of said bore, means for intermittently delivering fluid under pressure to said inlet line whereby the pressure of the fluid therein alternately rises and falls with the delivery or non-delivery of fluid thereto, means blocking the discharge of fluid from said outlet line below a predetermined fluid pressure therein, and non-return valve means in said bore for controlling the flow between said lines, said valve means being movable

5 in response to a predetermined differential fluid pressure force between said lines resulting from changes in the fluid pressure in said inlet line, said differential forces acting in one direction on said valve means to permit flow between said lines and seatable to block flow between said lines upon a pressure differential between said lines acting in the opposite direction, said valve means including a pressure sensitive diaphragm valve, means biasing said valve against said seat to block said flow, said valve being differentially acted upon by the pressures of the fluid in said lines and responsive to a differential between said line pressures acting in said opposite direction resulting from a lowering of the pressure in said inlet line below the said predetermined fluid pressure level at which said outlet line is blocked for ballooning of said diaphragm to a shape reducing the residual pressure in said outlet line subsequent to the seating of said valve, and means operable above a predetermined residual pressure in said outlet line to limit movement of said diaphragm toward said inlet.
